DISTILLATION OF TETRAMETHYL LEAD-ACETONITRILE AZEOTROPE WITH THERMAL STABILIZER

John Francis Hannan, Wilmington, Del., assignor to E. I. du Pont de Nemours and Company, Wilmington, Del., a corporation of Delaware

Filed Feb. 24, 1966, Ser. No. 529,879
4 Claims. (Cl. 203—6)

ABSTRACT OF THE DISCLOSURE

Distillation of tetramethyl lead-acetonitrile azeotropes with the addition of a thermal stabilizer at the top of the distillation column.

Background of the invention

This invention relates to the distillation of tetramethyl lead-acetonitrile azeotropes, and more particularly, to a novel method of stabilizing tetramethyl lead during distillation of tetramethyl lead-acetonitrile azeotropes in which the thermal stabilizer is introduced separately into the distillation unit.

Tetramethyl lead is well known as a valuable antiknock agent for motor fuels. It has a normal boiling point of 110° C., but is highly unstable at elevated temperatures. Overheating can lead to violent decomposition. However, methods are known for reducing this thermal decomposition hazard. For example, in U.S. Patent 3,049,558, Cook et al. discloses compounds which stabilized tetramethyl lead when added in small amounts. Listed compounds include saturated and unsaturated aliphatic and aromatic hydrocarbons boiling in the range of 90° to 150° C.

Recently Smeltz, in U.S. application Ser. No. 532,973, filed Feb. 1, 1966, described a novel tetramethyl lead distillation method wherein tetramethyl lead in the presence of acetonitrile forms azeotropes that distill at temperatures below the normal boiling point of either component. Smeltz also disclosed that when a volatile thermal stabilizer is present in the starting solution, it forms a binary azeotrope with the acetonitrile which codistills with the tetramethyl lead-acetonitrile azeotrope. However, in practice, it has been found that when stabilizing amounts of stabilizer are present in the feed, only a small fraction actually codistills with the tetramethyl lead, apparently due to alteration of volatilities when all of the components are present together. Thus, a significant portion of the stabilizer does not appear in the distillate thereby reducing the amount of tetramethyl lead stabilization there and requiring recovery of substantial amounts of stabilizer from the still bottoms.

Further, as Smeltz also disclosed, the distillate tends to separate into two liquid phases, the upper layer being poor in tetramethyl lead while the lower is rich in tetramethyl lead, often containing more than 85% tetramethyl lead. Because only a small amount of the stabilizer codistills with the tetramethyl lead and acetonitrile, an unsafe situation is created, there being insufficient stabilizer in the lower layer to adequately stabilize the high tetramethyl lead content. It has now been found that such phase separation also tends to occur within the fractionating column itself. Thus, these azeotropic distillations present a serious explosion hazard, even though stabilizing proportions of volatile stabilizer are initially present in the distillation feed.

Description of the invention

It is an object of this invention to provide an economical method for completely stabilizing tetramethyl lead during fractional distillation of tetramethyl lead-acetonitrile azeo-

2

trope. This and other objects will become apparent from the following description of this invention.

It has now been discovered that tetramethyl lead-acetonitrile azeotropes can be economically distilled under completely safe conditions by

(a) Feeding into a fractional distillation unit containing a reboiler, a fractionating column having at least about 3 theoretical plates and an overhead distillate takeoff, a tetramethyl lead composition containing acetonitrile in azeotrope-forming proportions, at a point at least about 1 theoretical plate above the reboiler,

(b) Simultaneously feeding at least about 0.25 part by weight, per part of tetramethyl lead in the feed composition, of a volatile thermal stabilizer for tetramethyl lead at a point not below the top of the column and at least about 2 theoretical plates above the tetramethyl lead composition feed point, whereby the stabilizer is distributed throughout the distillation column in tetramethyl lead-stabilizing proportions, and

(c) Recovering overhead a distillate which contains substantially all the tetramethyl lead and stabilizer fed to the column and which, on separating into two phases, produces layers each having a tetramethyl lead to stabilizer weight ratio not greater than about 5:1.

In view of the teaching in the Smeltz application that the stabilizers form azeotropes with acetonitrile which codistill with the tetramethyl lead-acetonitrile azeotrope, it is quite surprising that the separate stabilizer feed technique of this invention significantly alters the distribution of stabilizer throughout the system. In spite of the fact that azeotropes are being formed, as evidenced by distillation of mixtures at temperatures below the boiling points of their components, it has been found in accordance with this invention that the composition of the distillate can be varied substantially by the manner in which the stabilizer is introduced.

Although adding a large excess of stabilizer to the feed composition might also provide stabilizing proportions throughout the distillation unit and in the distillate, this is a costly expedient involving the recovery of large amounts of stabilizer from the bottoms stream. In fact, it has been found that to provide the 4:1 tetramethyl lead to stabilizer ratio desirable for complete stabilization throughout the distillation, about one part of toluene per part of tetramethyl lead would be needed in the feed composition. This means about 75% of the added toluene would leave the column with the bottoms and would have to be recovered. In accordance with the present invention, the use of large excesses of stabilizer is avoided.

The figure schematically illustrates a typical embodiment for carrying out the process of this invention.

The tetramethyl lead compositions which are useful as feed material for the process of this invention are those containing acetonitrile in azeotrope-forming proportions. When no water is present, distillation of these compositions under fractionating conditions results in the formation of a binary azeotrope containing about 61.2% by weight tetramethyl lead and about 38.8% acetonitrile and boiling at 73.3° C. at normal atmospheric pressure. When water is present, a ternary azeotrope containing about 62% by weight tetramethyl lead, about 31% acetonitrile and about 7% water and boiling at 69° C. at atmospheric pressure is formed. When sufficient water is present to form the above ternary azeotrope, the feed composition may contain as little as about 0.5 part by weight of acetonitrile per part of tetramethyl lead. When insufficient water is present, the feed composition should contain at least about 0.63 part by weight of acetonitrile for each part of tetramethyl lead. Usually the composition contains at least about 1.7 parts of acetonitrile per part of tetramethyl lead and may contain rather large excesses

of the nitrile up to about 100 parts. Suitable tetramethyl lead-acetonitrile compositions can be prepared by adding the required amount of acetonitrile to tetramethyl lead-containing reaction products obtained by the reaction of methyl chloride with sodium-lead alloy as described by Jarvie et al. in U.S. Patent 3,048,160, by Tullio in U.S. Patent 3,072,694, and by Cook et al. in U.S. Patent 3,049,558.

The process of this invention is particularly directed to the use of tetramethyl lead-acetonitrile compositions obtained by electrolytically producing tetramethyl lead at a lead cathode as described by Silversmith and Sloan in U.S. Patent 3,197,392 and by Smeltz in copending U.S. application Ser. No. 377,312, filed June 23, 1964. These processes produce reaction mixtures containing unreacted methyl bromide, tetramethyl lead, acetonitrile, tetraalkyl ammonium bromide in which each alkyl group has 1-2 carbon atoms, and sometimes water. Normally before such mixtures are distilled in accordance with the present invention, the methyl bromide is first distilled off, usually in a separate stripping still at a 3° to 4° C. head temperature. After removal of the methyl bromide these solutions generally contain about 1 to 12% by weight tetramethyl lead, about 40 to 85% acetonitrile, about 5-30% tetraalkyl ammonium bromide and 0 to 6% water.

Substantially all the tetramethyl lead present in the feed distills off in the form of the azeotrope. Since acetonitrile normally boils at 81.6° C., any excess present stays behind under fractionating conditions. Likewise any tetraalkyl ammonium bromide present in the original catholyte composition is practically non-volatile and accumulates in the still bottoms.

Referring now to the figure, the tetramethyl lead-containing feed composition is pumped from tank 1 through heat exchanger 2 into the middle region of a conventional fractional distillation unit containing a reboiler 3 surrounded by a fractionating column 4 which may contain actual plates 5 or suitable packing. Stabilizer for the tetramethyl lead is pumped from storage tank 6 through heat exchanger 7 into the top of column 4.

The distillate take-off unit illustrated in the figure is of the offset type. Distillate is removed from the column through overhead distillate takeoff line 8 and passed to condenser 9. The condensed vapors are passed to decanter 10 where separation of the distillate into two layers takes place. The upper layer, which is rich in acetonitrile, is passed through heat exchanger 11 and returned to the column. The lower layer, which is rich in tetramethyl lead, is recovered via line 12 as a product of the process. Bottoms stream, which is primarily acetonitrile, is withdrawn from the reboiler via line 13.

The fractionating column should have at least three theoretical plates and preferably 5-15, but may have as many as about 25 or more. The inlet for the tetramethyl lead feed composition should be at least 1 and preferably 2-4 theoretical plates above the reboiler, so that the tetramethyl lead azeotropes can be efficiently stripped from the remaining feed.

The inlet for the stabilizer should be at a point not below the top of the column. The phrase "top of the column" refers to the uppermost plate in the column or, if the column does not contain actual plates, the top of the packing. Thus the stabilizer may be added at the top of the column or at some point above the top of the column such as the reflux zone. Of course the stabilizer could also be added with the distillate recycle provided it is added at a point not below the top of the column. This stabilizer inlet point should also be at least 2 theoretical plates, and preferably 3-7, but practically speaking not more than about 15 theoretical plates above the tetramethyl lead feed composition inlet point, whereby the stabilizer is substantially completely stripped from the system, with little or no stabilizer entering the bottoms.

The invention is illustrated below using toluene as the stabilizer. However, other known volatile stabilizers boil-

ing in the 70° to 160° C. range can also be used in accordance with this invention. Typical examples of suitable stabilizers include saturated and unsaturated aliphatic, alicyclic and aromatic hydrocarbons and halogenated hydrocarbons such as cyclohexane, n-heptane, 2-methylhexane, 3-methylhexane, heptene, methylhexene, n-octane, isoctane, octene, 3 - ethylhexane, 2,5 - dimethylhexene, 2,2,5 - trimethylhexane, 2,6-dimethylheptane, 4-ethylheptane, nonane, terpenes such as turpentine, benzene, ethylbenzene, styrene, the xylenes, ethylene dichloride, and mixtures thereof.

The stabilizer to tetramethyl lead ratio necessary for proper stabilization varies with the stabilizer and is determined by the usual thermal tests described in the Cook et al. patent cited above. A tetramethyl lead to stabilizer weight ratio not greater than about 5:1 provides good thermal stability in most cases. Preferably the ratio should be 4:1 or less.

Conveniently and preferably the process is conducted continuously, the stabilizer and tetramethyl lead composition streams being fed continuously to the column, distillate being taken off overhead continuously and the bottoms stream being removed from the reboiler continuously. Alternatively, the bottoms may be allowed to accumulate in the reboiler. The stabilizer and tetramethyl lead composition streams should be fed to the column simultaneously at rates that are consistent with the capacity of the column so as to avoid flooding and provide at least 0.25 part, and usually not more than about 0.4 part, stabilizer per part tetramethyl lead in the total feed. More than 0.4 part gives no particular benefit, although larger amounts may be used if desired without adverse effect.

Heat for the distillation may be provided solely by the column and its reboiler equipped with heating means or in part by the feed. For example, preheated tetramethyl lead composition can be fed to an insulated column, and the temperature and/or pressure within the column can be adjusted to cause the appearance of the azeotropic composition in the overhead. The stabilizer, which may be preheated if desired, can be fed to the column as liquid or injected as vapor.

Usually the distillation is conducted at about atmospheric pressure and head temperatures of about 69° to 89° C. Most commonly temperatures of about 72° to 77° C. are used. Reduced pressures and correspondingly lower temperatures may also be used, for example 100 mm. Hg (0.2 atmosphere) and 35° C.

An offset type distillation head is conveniently used. Distillate containing tetramethyl lead, a stabilizing proportion of stabilizer, acetonitrile and water, when present, is taken off continuously, usually at a reflux ratio of about 3:1 to 15:1 and preferably about 4:1 to 8:1. Distillates containing at least about 39% by weight tetramethyl lead separate into two distinct liquid phases at or just below the boiling point of the azeotrope. The upper layer is poor in tetramethyl lead, while the lower layer is rich in tetramethyl lead. The thermal stabilizer and water, when present, distribute themselves between the two layers.

The tetramethyl lead can be recovered from the total distillate by washing the distillate with water, which extracts the acetonitrile, leaving the tetramethyl lead and the thermal stabilizer. Preferably the distillate is first allowed to separate into two layers and the tetramethyl lead-poor upper layer is continuously returned to the column after reheating back to column temperature. At the same time, the lower tetramethyl lead-rich layer is continuously removed and washed with water to remove residual nitrile.

The bottoms stream is preferably removed continuously from the reboiler at a rate which is substantially the difference between the total feed rate and the distillate take off rate. This stream is substantially tetramethyl lead-free and stabilizer-free.

The overall result achieved in accordance with this invention is that substantially all the tetramethyl lead and all the stabilizer fed to the column is removed overhead.

Thus a tetramethyl lead-stabilizer composition is obtained directly in the desired proportions while substantially no tetramethyl lead or stabilizer is lost to the bottoms stream. Moreover, samples taken from the column during distillation show that within the column itself no unstable tetramethyl lead compositions exist. In the lower regions of the column where the stabilizer concentration is lowest, the overall compositions are so dilute in tetramethyl lead, due to the relatively large proportion of acetonitrile, that they present no explosion hazard.

Further up the column, in the middle and top regions, the tetramethyl lead content increases progressively due to the column enriching action. However, the stabilizer content also increases and, due to the stabilizer feeding technique of this invention, shows a progressively greater concentration gradient than the tetramethyl lead so that the amount of stabilizer corresponds to a stabilizing proportion at all times. Accordingly, tetramethyl lead to stabilizer ratios of not greater than 5:1, and preferably 4:1 or less, are readily maintained throughout the column and in the distillate.

The following examples, illustrating the novel process disclosed herein, are given without any intention that the invention be limited thereto. All parts and percentages are by weight.

EXAMPLE 1

The basic distillation unit used in this example contained a fractionating column, reboiler and variable reflux ratio distillation head. The column was a vacuum jacketed, Oldershaw cylindrical glass column having a one-inch inside diameter and 15 real plates spaced one inch apart, essentially as described by Collins et al. in Ind. and Eng. Chem. Qual. Ed., 18, No. 11, 673 (1946). The column was further fitted with sampling taps at every other plate, a feed stock inlet at five plates above the reboiler, and a stabilizer feed inlet above the uppermost plate and below the condenser. An automatic buret leading to the column through a microbellows pump and heat exchanger served to store, meter, and preheat the stabilizer to feed temperatures.

The reboiler was a 0.5 liter flask fitted with heating jacket, siphon draw-off tap for removing bottoms, and thermocouple well. The distillation head was equipped

with a timer-operated plunger for controlling distillate takeoff.

The plate efficiency of the column was found to be 25 to 30% using the vapor-liquid equilibrium data for acetonitrile-water mixtures of Othmer et al. in Ind. and Eng. Chem., 39, 1175-1177 (1947). This efficiency rating corresponds to about 2.5-3 theoretical plates separating the tetramethyl lead and stabilizer feed points.

A tetramethyl lead-acetonitrile-water composition, as described in the table below, was preheated to 70° C., and fed to the column through the feed stock inlet at a 20 gms./min. rate. Simultaneously toluene, preheated to 70° C., was fed to the top of the column at a 0.32 gm./min. rate, corresponding to a 4:1 tetramethyl lead to toluene weight ratio. The reboiler was heated to provide a bottoms temperature of about 79° C. With the column operating at a 74° C. head temperature and a 10:1 reflux ratio, 2 grams of distillate per minute were taken off overhead while simultaneously 10 grams of bottoms per minute were removed from the reboiler.

The total composition of the distillate is shown in the table. On cooling, this distillate separated into an upper tetramethyl lead-poor layer and a lower tetramethyl lead-rich layer. The total distillate contained tetramethyl lead and toluene in about a 4:1 weight ratio.

A comparative run, not within the scope of this invention, was made by repeating the above experiment except that the toluene was combined with the tetramethyl lead feed stock and introduced into the column at the tetramethyl lead composition feed point. The tetramethyl lead content of the feed stock and the tetramethyl lead to toluene feed ratio were slightly lower than in the above example as indicated in the table, which should have had a favorable influence on the result. The tetramethyl lead to toluene weight ratio of the resulting total distillate was an unsafe 9:1.

EXAMPLE 2

Example 1 was repeated except that the height of the column was increased to 20 real plates and other variables were changed as indicated in the table. The toluene feed point was 3.75-4.5 theoretical plates above the tetramethyl lead feed point.

EXAMPLE 3

Example 1 was repeated except that a modified fractional distillation unit was used and the operating variables were changed as indicated in the table. The height of the column was increased to 20 real plates and the condenser was an off-set type mounted in an off-center extension from the top of the distillation column. The distillate was allowed to stratify, the lower tetramethyl lead-rich layer was recovered and analyzed, and the upper tetramethyl lead-poor layer was recycled to the top of the column via a 70° C. heat exchanger, by means of a micro-bellows pump.

The table above, in which "TML" represents tetramethyl lead, summarizes the above experiments and results.

From the above table, it can be seen that the toluene recovery ratio (toluene in distillate/toluene in bottoms) was dramatically improved when toluene was fed near the top of the column in accordance with this invention. In contrast, conventional toluene feed in the Comparative Run resulted in about half of the toluene being lost to the bottoms.

The above data also shows that introducing the toluene with the tetramethyl lead feed stock (Comparative Run) does not provide sufficient toluene in the distillate to ensure complete tetramethyl lead stabilization. The 8:1 tetramethyl lead to toluene ratio in the lower layer of the Comparative Run presents a hazardous situation. Moreover, this explosion hazard exists in the column itself since phase separation also occurs there, particularly at the uppermost plates. In contrast, tetramethyl lead to toluene ratios are readily maintained within safe limits both in the column and the distillate in accordance with the present invention. In actual practice, Example 1 would be run with a tetramethyl lead to toluene feed ratio of about 3.4:1, as in the Comparative Run, which would ensure completely stable conditions in the tetramethyl-lead-rich lower layer of the distillate.

EXAMPLE 4

The tetramethyl lead feed stock employed in this example was obtained from a tetramethyl lead-rich catholyte produced according to the electrolytic process described by Smelt in copending application, Ser. No. 377,312, filed June 23, 1964. The original catholyte leaving the Smeltz cell contained 5% tetramethyl lead, 57% acetonitrile, 3% water, 20% tetraethyl ammonium bromide and 15% methyl bromide. The methyl bromide content was distilled off in a conventional distillation column and the residue was used as feed stock for the distillation in accordance with this invention.

The feed stock containing 6% tetramethyl lead, 69.2% acetonitrile, 5.3% water and 19.5% tetraethyl ammonium bromide, was preheated to 65° C. and fed at a 4 gal./hr. (ca. 35 lbs./hr.) rate to the mid point of a lagged 4 in. x 10 ft. 316 stainless steel column packed with 1/4 in. Intalox ceramic saddles and having 10 theoretical plates. The column was fitted with a 20 gal. 316 stainless steel reboiler and a 316 stainless steel shell and tube type condenser. Simultaneously toluene at 25° C. was fed at the top of the column at a 0.5 lb./hr. rate. The total feed was allowed to distill in the column at a reflux ratio of about 10:1. The tetramethyl lead-poor upper layer of the distillate was recycled to the column while the tetramethyl

lead-rich lower layer was recovered at the rate of 2.5 to 3 lbs./hr. A bottoms stream was removed from the reboiler at the rate of 32 to 33 lbs./hour.

The recovered distillate contained 76% tetramethyl lead, 18% toluene, 5.5% acetonitrile and 0.5% water for a tetramethyl lead to toluene ratio of about 4:1. Washing with water removed the nitrile and residual water, leaving a stabilized tetramethyl lead-toluene composition suitable for antiknock blending. The bottoms contained 69% acetonitrile, 6% water and 26% tetraethyl ammonium bromide with no detectable tetramethyl lead or toluene.

Although the invention has been described and exemplified by way of specific embodiments, it is not intended that it be limited thereto. For instance, other stabilizers than toluene could be used in the above examples with essentially the same result. It is to be understood that the invention includes all modifications and variations coming within the scope of the following claims.

The embodiments of the invention in which an exclusive property or privilege is claimed are defined as follows:

1. A method of distilling tetramethyl lead-acetonitrile azeotropes which comprises
  - (a) feeding into a fractional distillation unit containing a reboiler, a fractionating column having at least 3 theoretical plates and an overhead distillate take-off, a tetramethyl lead composition containing acetonitrile in azeotrope-forming proportions at a point at least 1 theoretical plate above the reboiler.
  - (b) simultaneously feeding at least 0.25 part by weight, per part of tetramethyl lead in the feed composition, of a volatile thermal stabilizer for tetramethyl lead at a point not below the top of the column and a least 2 theoretical plates above the tetramethyl lead composition feed point, whereby the stabilizer is distributed throughout the distillation column in tetramethyl lead-stabilizing proportions, and
  - (c) recovering overhead a distillate which contains substantially all the tetramethyl lead and stabilizer fed to the column and which, on separating into two phases, produces layers each having a tetramethyl lead to stabilizer weight ratio not greater than 5:1.
2. The method of claim 1 in which the tetramethyl lead composition is fed into the fractional distillation unit 2 to 4 theoretical plates above the reboiler and the thermal stabilizer is fed 3 to 7 theoretical plates above the tetramethyl lead composition feed point.
3. The method of claim 2 in which the thermal stabilizer is toluene.
4. The method of claim 3 in which 0.25 to 0.4 part of toluene is added per part of tetramethyl lead in the feed.
